UNITED STATES PATENT OFFICE.

WILLIAM L. MINICK, JR., AND BUFORD F. MENTZER, OF WAYNESBORO, PENNSYLVANIA.

MILK-BOTTLE CAP.

1,409,194.

Specification of Letters Patent. Patented Mar. 14, 1922.

Application filed February 15, 1921. Serial No. 445,212.

To all whom it may concern:

Be it known that we, WILLIAM L. MINICK, Jr., and BUFORD F. MENTZER, citizens of the United States, residing at Waynesboro, in the county of Franklin and State of Pennsylvania, have invented certain new and useful Improvements in a Milk-Bottle Cap, of which the following is a specification.

This invention relates to milk bottle caps and more particularly to an improved closure for mounting in the open top of a milk bottle whereby the bottle will be air tight.

One of the objects of the invention is to provide a milk bottle closure of this character which will consist of a simple and inexpensive piece of suitable material shaped to conveniently fit the neck of the bottle and have a convenient finger grip whereby the closure may be readily removed.

Another object of the invention is to provide a closure of this character which will be constructed whereby the finger grip may be utilized as a reinforcing member whereby strength is given to the closure disk so that the life of the same will be increased.

Other objects of the invention will appear upon consideration of the following detail description and accompanying drawings, wherein:

Figure 1 is a cross section through a portion of a bottle showing the invention applied thereto.

Figure 2 is a plan view of the same.

Figure 3 is a perspective view of the device constructed in accordance with my invention.

Referring to the drawing by numerals, the bottle neck Fig. 1 is of the usual construction having the usual annular recess whereby a closure member may be placed in position to close the open end of the bottle. This closure member consists of a piece of cardboard or other suitable material, it being understood that material of any preferred kind may be utilized in constructing the device. The piece consists of a substantially circular disk 1, folded at the center to form a diametrically extending rib 2 of substantially T shape which serves as a finger grip in addition to a reinforcing member. This member 2 is formed by folding the central portion of the material on lines 5 and 6 as shown to advantage in Figs. 1 and 3 of the drawing thereby forming a substantially wide strip 3 which when the stopper is pressed into its

normal position provides a diametrically extending rib having recesses 4 on each side constituting finger engaging means for grasping the rib. So folding the strip provides a triple thickness of material at the center of the stopper increasing the strength of the disk and permitting the two semi-circular portions of the disk 1 to be folded toward or away from each other so that the disk may be conveniently inserted in the neck of the bottle. The ends of said T shaped rib engage the inner periphery of the bottle, as shown in Fig. 2.

When the device is in use, the finger grip member 3 will be held in the fingers, the fingers being inserted in the recesses 4 on opposite sides thereof and the disk pressed downwardly into position in the recess in the neck of the bottle as shown in Fig. 1 thus causing the neck to be entirely closed. The diametrically extending strip in addition to serving as a finger grip also serves as a reinforcement for the disk so that the life of the disk is materially increased. Furthermore the relatively wide surface of the portion 3 provides a convenient space for receiving advertising matter.

While the above shows the preferred embodiment of the invention it will be understood that variations may be made in the dimensions and size of the closure to suit conditions.

What is claimed is:

1. A milk bottle cap comprising a strip of material folded to provide a transverse rib of substantially T shape in cross section, said rib forming finger engaging means for removing said cap, the ends of said T shape portion engaging the inner periphery of the bottle.

2. A milk bottle cap comprising a piece of pliable material, a plurality of parallel bends across its center which when folded provide a circular disc having a flat diametrically extending rib of substantially T shape in cross section, the ends of said T shape portion engaging the inner periphery of the bottle.

In testimony whereof, we have affixed our signatures in the presence of two witnesses.

WILLIAM L. MINICK, JR.
BUFORD F. MENTZER.

Witnesses:

JOHN B. GEISER,
W. L. MINICK.
